UNITED STATES PATENT OFFICE.

VOTAW S. DURBIN, OF ST. LOUIS, MISSOURI, ASSIGNOR TO DURBIN AUTOMATIC TRAIN PIPE CONNECTOR COMPANY, OF ST. LOUIS, MISSOURI, A CORPORATION OF ARIZONA.

AUTOMATIC TRAIN-PIPE COUPLING.

1,138,359.

Specification of Letters Patent.

Patented May 4, 1915.

Application filed January 6, 1913. Serial No. 740,313.

To all whom it may concern:

Be it known that I, VOTAW S. DURBIN, a citizen of the United States, residing in the city of St. Louis, State of Missouri, have invented new and useful Improvements in Automatic Train-Pipe Couplers, of which the following is a specification.

This invention relates to certain new and useful improvements in automatic train pipe 10 couplings, and has for its object to simplify the construction of a device of this character and at the same time to increase the efficiency thereof by insuring reliability in operation under all normal conditions of 15 service.

In addition to improvements relating to the device as a whole the present invention in detail comprises a novel construction of supporting bracket and a novel manner 20 of supporting the plunger of the coupler head therein; an improved construction of pipe section or nipple and novel means for holding the same in position in the coupler head; and a novel construction of the pyramidal projections of the coupler heads 25 whereby their meeting faces will mutually tend to guide the projections into the appropriate recesses or openings in the coupler head.

30 In the accompanying drawings—Figure 1 is a view in side elevation showing two interlocked car couplers and two of my improved train pipe couplers interlocked and in the relative position they occupy with respect to the car coupler; Fig. 2 is a plan view showing two of my improved train pipe couplers interlocked, a portion of both couplers being broken away to illustrate the manner of automatically locking them in engagement; 35 Fig. 3 is a central longitudinal sectional view of the same; Fig. 4 is a view in front elevation of a car coupler and one of my improved coupler heads; Fig. 5 is a face view of a portion of the coupler head, the pyramidal projection thereof being sectioned in a vertical plane to illustrate the construction of the inner face thereof; and Fig. 6 is a detail view of one of the nipples.

40 Referring now to these drawings, the numerals 1, 2, indicate, generally, two interlocked car couplers and the numerals 3, 4, two interlocked train pipe coupler heads which, as shown, are positioned below the car couplers. 45 Each of my improved couplers is of the same construction, and is mounted in the

same way on the respective cars, and a description of one, and the manner of mounting and operating the same, will apply to the other. The coupler head 3 is provided on its rear side with a projection 5 which is 50 pivotally mounted in the outer end of a hollow plunger 6 by means of a pivot pin 7. The numeral 8 indicates a bracket which is provided with a flanged top 9 suitably shaped and apertured whereby it may be 55 securely fastened to frame members 10 depending from the car body. Two converging legs or webs 11 of the bracket are bifurcated in their lower portion to form yokes, the arms 12, 13, of which straddle 60 the plunger 6, and at their point of convergence on either side of said plunger the said yokes are provided with an aperture through which passes a pivot pin 14, which 65 pivot pin likewise extends through slots 15 formed in opposite sides of the plunger 6 at the rear end thereof. Mounted in the plunger is a coil spring 16, the opposite ends of which encircle and rest against headed sleeves 17, 18, said sleeves being apertured 70 to permit the passage therethrough of conductors 19 which pass to the electrical contacts 20. These latter form no part of the 75 present invention. The headed end of the sleeve 17 rests against the pivot pin 14, and 80 the opening in the head thereof is suitably flared, as indicated at 21, to permit the conductors 19 to pass around the pivot pin 14 and to prevent abrading contact thereof with the pivot pin 14 or sleeve 17. The head 85 of the sleeve 18 is provided with a similar flared opening to permit the conductors to pass around the pivot pin 7, this sleeve resting against the flanged inner end of the plunger and the end of the projection 5. On 90 its outer side the bracket 8 has a vertically disposed leg 22 which, at its lower end, is bifurcated to provide an opening for the passage of the plunger 6, the two members of the yoke thus formed being integrally 95 united beneath the plunger 6 with a cup 23, the lower end of which is apertured to form a guide for a plunger 24, the upper end of which is supported on a coil spring 25. The 100 upper end of the plunger 24 is provided with a screw-threaded aperture 26 in which is screwed a bolt 27 having a head 28 which normally engages the under side of the plunger 6 and supports the same. A lock nut 29 holds the bolt 27 in adjusted positions. By 110

this construction the plunger 6 is held normally in a horizontal position but is free to move upward or downward a limited distance about its pivot 14, the latter movement being against the resistance of the spring 25. Should this spring, after long continued use, lose somewhat of its strength and allow the plunger 6 to fall below the horizontal the lock nut 29 is loosened and the bolt 27 unscrewed a sufficient distance to make up for the depression of the spring, when the lock nut 29 is again turned home.

Normally the coupler heads 3 and 4 project some distance beyond the face of the respective coupler heads 1 and 2, so that the coupler heads 3 and 4 are brought into engagement before the coupler heads 1 and 2. As the coupler heads 3 and 4 are thus brought into engagement the plunger 6 is pressed backward against the resistance of the spring 16, the slot 15 riding over the pivot pin 14. During the time, therefore, that the said coupler heads are in interlocked relation the spring 16 of each plunger is exerting its force to maintain a firm contact between the meeting surfaces of the two heads. In order to prevent the accidental separation of the coupler heads 3 and 4 I provide the automatic locking means now to be briefly described, but which locking means are not a part of the present invention.

As shown by Fig. 4, each coupler head is provided with a pyramidal projection 30 and with an opening 31 which latter is designed to receive the corresponding pyramidal projection on the companion coupler head. The pyramidal projections 30 are hollow, and pivotally mounted at 32 on the inner side of each coupler head is a lock-lever 33 having a hook 34 which is adapted to project through an opening 35 in the wall of the projection 30 and to engage over the rim 36 surrounding the opening 31 of the companion coupler head. Pivotally secured at 37 to the outer end of the lever 33 is a rod 38, the rear end of which is pivotally connected at 39 to the outer end of a link arm 40 which extends outward at right angles to a vertically disposed pin 41 which is mounted at the extreme inner end of the plunger 6, the said inner end of the plunger being cut away, as indicated at 42, to provide a space for the play of the arm 40. The arm 40 has a hub 43 which is rotatably mounted on the pin 41. The numeral 44 indicates a coil spring which encircles the pin 41 and has one end 45 secured in the end of the plunger 6 and its other end 46 bearing against the arm 40 in such manner as to tend normally to press the rod 38 inward, or to the position it is shown to occupy in Fig. 2, thereby forcing the hook 34 through the opening 35. Formed integral with the bracket 8 and projecting from the

rear side thereof is a lug 47 which in operation is adapted to engage the inner side of the arm 40. This occurs when the cars are separated. In such operation the bracket 8 will, of course, first be moved backward by 70 the car and in such movement the lug 47 will strike the arm 40 and draw the rod 38 backward, thereby turning the hook 34 out of engagement with the rim 36 so that in the continued separating movement of the cars 75 the two coupler heads 3 and 4 may be drawn apart. As these coupler heads are brought together the plunger 6 is forced backward carrying the arm 40 out of engagement with the lug 47 and permitting the spring 80 44 to again force the rod 38 forward or toward the coupler heads to turn the hook 34 outward and into engagement with the rim 36.

An important feature of the present invention relates to the manner of securing the pipe connectors or nipples in the coupler heads. These nipples are for the purpose of connecting the various train pipes with the coupler head, and with a companion nipple 96 to form a conduit through the interlock coupler heads, the numeral 48 indicates the nipple for the signal pipe, the numeral 49 that for the main train pipe and the numeral 50 that for the steam pipe. Each of these nipples has the same construction and a description of one will suffice. Each of these nipples is in the form of an "elbow," having an outer screw-threaded cap piece 51 for connection with the end of the train pipe, a collar 52 for resting against the face of the coupler head, and an engaging portion 53 which is inserted in a suitable aperture in the coupler head and preferably bears against a rubber or other gasket 54, which gasket constitutes the engaging surface proper. At the bend of the nipple I provide a rounded lug 55 which engages in a socket formed in the end of a bridge piece 56, the other end of which rests on a lug 57 on the rear side of the coupler head. A bolt 58 secured in the coupler head projects through the bridge piece and by means of a nut 59 and a washer 60 the bridge piece 56 may be screwed down into firm contact with the lug 55 to hold the nipple 48 in a fixed position in the coupler head. By loosening the nut 59 the nipple may be turned to any desired position to have the pipe secured thereto, after which the bridge piece will be secured in position as above described. In the case of the nipples 49 and 50 a single bridge piece 61 answers for both nipples, engaging the lugs 62, 63, thereof.

In order to insure that the pyramidal projection 30 shall enter the corresponding opening 31 of the companion coupler head, I provide the face of each pyramidal projection adjacent to the opening 31 with a flattened depressed portion or recess 64, as 120

shown in Fig. 5, which provides ribs 65 at either side thereof which tend to prevent the meeting faces from sliding laterally past each other.

5. I claim:

1. In a train pipe coupler, a bracket, a coupling member pivotally mounted therein, said bracket having a rigid portion extending downward under said coupling member, 10 and a yieldable support for said coupling member on said downwardly extending portion of the bracket.
2. In a train pipe coupler, a bracket, a coupling member pivotally mounted in said bracket, a casing carried by the bracket, a spring pressed plunger working in said casing, and an adjusting bolt mounted in said plunger and adapted to support said coupling member.
20. 3. In a train pipe coupler, a bracket, a hollow plunger mounted therein and having an elongated opening, a pivot pin mounted in the bracket and extending through said opening, a coil spring mounted in the 25 plunger and extending between said pivot pin and the end of the plunger, a coupler head mounted on said plunger, and a yielding support mounted on the bracket and engaging the under side of said plunger.
30. 4. In a train pipe coupler, in combination with the coupler head, an elbow-shaped, pipe-connecting nipple having one end portion rotatably mounted in the coupler head, a lug on said nipple, a bolt mounted on the 35 coupler head and having a screw-threaded outer end, a bridge piece slidably mounted on said bolt and having a socket for engaging said lug, and a nut for said bolt whereby to clamp the bridge piece in position.
40. 5. In a train pipe coupler, in combination with a coupler head having an aperture, an elbow-shaped, pipe-connecting nipple having a straight portion rotatably mounted in said aperture and provided on its exterior with a lug located substantially in the plane of the axis of said straight portion, a bolt mounted on the coupler head and having a screw-threaded outer end, a 45 bridge piece slidably mounted on said bolt and having a socket for receiving said lug, and a nut for said bolt whereby to clamp the bridge piece in position.
6. In a train pipe coupler, a coupler head having a pyramidal projection and adjacent thereto an opening for receiving a pyramidal projection on a mating coupler head, 55 said pyramidal projection having its side adjacent to the opening provided with a guide for the projection of the companion 60 coupler head.
7. In a train pipe coupler, a coupler head having a pyramidal projection and adjacent thereto an opening for receiving a pyramidal projection on a mating coupler 65 head, said pyramidal projection having its side adjacent to said opening provided with a depressed flat portion to form a guide for the meeting face of the projection of the companion coupler head.
8. In a train pipe coupler, a bracket, a coupling member having a pivotal engagement therewith, said bracket having a rigid portion underhanging said coupling member, and a yieldable support on said underhanging portion of the bracket, said coupling member resting slidably on said support.
9. In a train pipe coupler, a bracket, a coupling member having a pivotal engagement therewith, said bracket having a rigid portion underhanging said coupling member, a yieldable support on said underhanging portion of the bracket, and a member vertically adjustable on said yieldable support 75 slidably engaging the under side of said coupling member.
10. In a train pipe coupler, a bracket, a coupling member having a longitudinal 80 slidable and vertical pivotal engagement near its inner end with said bracket, said bracket having a rigid extension underhanging said coupling member a spring-pressed, vertically-movable plunger on said rigid extension, and a member vertically- 85 adjustable on said plunger slidably engaging the under side of said coupling member forward of the place of pivotal engagement of said coupling member with said bracket.

In testimony whereof, I have hereunto set 100 my hand in presence of two subscribing witnesses.

VOTAW S. DURBIN.
